CLAMP FOR A LAMP

Louis Weinreb, Chicago, Ill.

Application May 3, 1938, Serial No. 205,769

2 Claims. (Cl. 24—263)

This invention relates to a clamp for attaching an article like a lamp to an article of furniture, such as a chair, a divan, etc.

One object of the invention is to furnish a 5 permanently attached lamp to a chair or other similar articles of furniture, so that, when the chair or article of furniture is moved it will not disturb the relative position of the lamp, and that will maintain the relationship of the lamp as set, 10 placed, or attached to the article of furniture.

Another and main object of the invention is 15 the provision of an automatic telescopic clamp which will permit of its being universally attachable to the back of an article of furniture like a chair or other similar article of furniture, and being adapted so that when the article of 20 furniture is moved about the lamp relationship will not be disturbed, nor the lamp position interfered with.

Another object is the provision of a unique 25 clamping means to take different widths of the backs of articles of furniture as heretofore mentioned.

A still further object of the invention is the 30 provision of a simple, practical, efficient article which is also cheap to manufacture and attach for the purpose hereinafter to be described.

The foregoing and other objects and advantages 35 of the invention will become apparent from the following description and the accompanying drawing, wherein I have shown an embodiment of the invention, and wherein like numerals designate like parts.

Fig. 1 is an isometric view of my invention as 40 attached to an article of furniture shown in phantom.

Fig. 2 is a detailed front view of my invention partly in cross-section.

Fig. 3 is a top plan view looking on the line 45 3—3 of Figure 2.

Fig. 4 is an external view of the universal joint shown in Figure 2.

Fig. 5 is a ratchet or serrated adjusting means 45 which may be used in place of the universal joint shown in Figure 4.

Fig. 6 is a longitudinal cross-sectional view on the line 6—6 of Figure 5.

Fig. 7 is a front view of a novel construction of my clamping means arranged to be adapted to 50 articles of furniture that have diverse widths of backs.

Fig. 8 is a fragmentary front view portion showing how my invention could be permanently attached to the back of an article of furniture.

55 By referring to the drawing in Figure 1, a chair,

or other similar article of furniture is designated by the numeral 9 to which is attached my invention generally designated by the numeral 10, and showing the extension of the wire 11, terminating with a male plug to be attached to a wall receptacle or other source of electrical current supply. 5

By referring to Figure 2 where my invention is shown in greater detail, 12 designates a standard form of universal socket joint which is customarily employed in electrical work for attaching lamps or other similar devices, 47 designating the socket generally employed for receiving an electric bulb. 10

The universal joint 12 is attached to a piece of tubing designated by 13 which is curved in a suitable fashion as shown at Figure 2 and which terminates at its other end in a threaded portion to fit the thread 15 of a ball member 14, the said end has above it a hexagonal section designated by 39 used for tightening up to the ball member 14 to which it is assembled. 15

The ball 14 provides the universal joint in cooperation with the other parts designated for this purpose namely; the knurled nut 16 and the nut 17, the nut 17 having an internal thread 19 to fit the threaded extension of member 39, and attached to the nut 16 by virtue of thread 17'. These two nuts are recessed that is, nut 16 is recessed in such a manner as to provide universal action to the ball member 14, and nut 17 is recessed to retain an expansion spring or other spring means designated by 18, which tends to maintain the position to which it is desirable to set the lamp once it is attached. 20 25 30

The lamp bulb socket 47 is also provided with a similar universal joint 12, so that by using the two universal joints designated at 12 and 14 it will be noted that any desired universal position can be readily obtained in order to suit the convenience of the one using this invention in the 40 most advantageous manner. 35

This entire assembly is then attached to a tubing member 39, which extends for a sufficient length suitable for the purpose needed and which terminates in a threaded portion 31 to receive a square locking nut 32. Before assembling the clamping means to this device there is attached to the tubing member 39 a collar designated by 21 and attached by a set screw. It will be noticed that the tubing member 39 has a flange 22, and provides a suitable means for retaining the clamping member 23 so that it can rotate within 180° as shown more clearly in Figure 7. 45 50 55

This clamping member 23 has one extension 24 which is slightly bent and an extension 25 which 55

is also bent as shown at Figure 7, and it will be seen that the extension 24 is longer than the extension 25, in order to accommodate the different widths of backs of articles of furniture. If 5 a wider back is used as an upholstered chair, it would be more advantageous to use the extension 24 of the clamp 23, to attach to the article or, if the article has a narrow back as the one shown and indicated at 9 it will be more advantageous 10 to turn the clamp 180° to the dotted position indicated whereby the bent portion 25 will accommodate more readily a narrow back of an article 15 of furniture.

This clamping means is further attached to a square tubing generally designated by the numeral 26 which has a partly closed top portion or ledge 27 and a hole 28 to suit the diameter of the tubing member 30. The coil spring 29 is then attached surrounding the tubing member 30 after 20 which the spring is compressed in order to permit the threaded extension 31 of the tube 30 to be assembled with the square nut 32 the nut then being permitted to slip into the square hole 33 of the square tubing 26. At one surface of the 25 square tubing 26 is attached the other component clamping element designated by 34 which has a bent portion 35 and dulled teeth 36 or preferably a knurled edge in order to grip the lower rung of an article of furniture or the underneath portion of the back member.

Fig. 3 designates more clearly the teeth 36 and the cross-sectional arrangement of the tubing 26 and the tubing member 30 in relation with the spring 29.

It will be noticed that the electrical connection is made from the socket portion 47 thru the hollow portion of the tubing 13 thru the universal ball joint 14 down thru the tubing 30 and out thru to the male plug which is to be plugged 40 into a wall receptacle or other source of electrical current supply.

Instead of using the ball joint 14, one or more ratchet clamping type of joint may be utilized as illustrated in Figures 5 and 6 where the tubing member 13 is threaded into a member designated 45 by 38 which has a serrated surface or saw teeth designated by 42 having also a threaded male extension designated by 40.

The component member for affecting a relative setting of this joint which works and operates 50 only in one plane, is the portion 41 which has a clearance hole 48 in order to receive the threaded male extension 40. It also has a suitable threaded female portion to receive the tubing member 38 the purpose of the nut 37 being readily obvious, that is, namely, once the desired 55 position has been established the nut 37 is used for the purpose of locking that particular setting or position.

In Figure 8 I designate a simplified means of 60 permanent attachment of my invention to an article of furniture which shows the tubing member 13 being clamped in a bracket designated by 43, which has 3 holes drilled in it to receive the wood screws 45 which are to be attached to the 65 back of the chair 9 or other article of furniture that it may be desirable to attach this invention to, and a set screw member 46 in a boss 44 which is for the purpose of adjusting the tubing 13 and incidently the lamp bulb height, in an upward 70 and downward direction.

I believe that in showing a number of ways of attaching a source of illumination to a chair,

either adjustably in an upward or downward direction or in a single plane by virtue of the joint shown in Figure 5, or in a universally acting arrangement as shown and illustrated in Figure 2 and other corresponding explanatory views, I have made this description completely explicit.

It has been my experience that a device of this type is highly desirable for in order to obtain lighting effects to equal what I have attempted to do with my invention when one places a floor lamp behind a chair it is in the way, it does not furnish the light at the proper place, and when one decides to move about or move the article of furniture certain damage may be done by overthrowing the lamp or other source of supply which may be used in the ordinary manner.

With my device I can move about on my chair, move my chair in any position, adjust the lamp to focus the illumination at the particular point where I like to have it, and in that way I believe I have illustrated and created a most advantageous device for the purpose outlined.

It is believed to be obvious that I have provided a novel clamping device which is substantially universal in its action, which is simple and inexpensive to manufacture.

Altho I have illustrated preferred forms of the invention it will be apparent to those in the art that this invention is not limited to such forms, and that I reserve the right to all modifications and alterations which may be made without departing from the spirit of the invention or from the scope of the subjoined claims.

Having thus described my invention what I claim as new and desire to secure by Letters Patent is:

1. In a device of the character described, universal clamping means, comprising, a tubular member of square section open at one end and provided with a shoulder portion at its other end, a circular tube member threaded at one end slidably mounted in said square tube member, a square nut secured to the threaded end of said circular tube member and slidably fitted within the said square tube member, spring means intermediately confined between the said square nut member and the shoulder portion of the said square tube member, a clamping member rigidly secured laterally of the open end of said square tube, and an auxiliary clamp member rotatably mounted on the exposed portion of said circular tube member.

2. In a device of the character described, universal clamping means, comprising, a tubular member of square section open at one end and provided with a shoulder portion at its other end, a circular tube member threaded at one end slidably mounted in said square tube member, a square nut secured to the threaded end of said circular tube member and slidably fitted within the said square tube member, spring means intermediately confined between the said square nut member and the shoulder portion of the said square tube member, a clamping member rigidly secured laterally of the open end of said square tube, and an auxiliary clamp member rotatably mounted on the exposed portion of said circular tube member, the said auxiliary clamp member eccentrically mounted so as to provide a longer and shorter extension adapted to accommodate the back structure of articles of furniture having varied thicknesses.

LOUIS WEINREB.
